UNITED STATES PATENT OFFICE.

HARRY FOSTER LEES, OF NEW YORK, N. Y., ASSIGNOR TO JOHN R. CLANCY, OF SYRACUSE, NEW YORK.

STAGE-SCREW.

1,055,056.

Specification of Letters Patent. Patented Mar. 4, 1913.

Application filed July 25, 1912. Serial No. 711,598.

To all whom it may concern:

Be it known that I, HARRY FOSTER LEES, a citizen of the United States, residing at New York city, in the county of New York and State of New York, have invented new and useful Improvements in Stage-Screws, of which the following is a specification.

My invention relates to an improved form of stage screw adapted for employment with stage scenery braces as customarily used, and consists in a simple device of few and substantial parts which are economically made and which in use will have important advantages over types of screws heretofore used.

Among the important advantages of the present invention are first, its capability of use with the ordinary single piece foot iron, to which it is permanently clamped so as always to be in proper position for immediate use without danger of becoming lost or misplaced; second, the convenient provision made for replacing of the screws when they become worn or damaged, and finally its adaptation to use as an ordinary portable stage screw when desirable for special situations, etc. My invention is thus equally suited for dual use as a permanent and fixed part of scenery brace and as a separable hand screw of the ordinary type but with the additional feature of a detachable screw.

These and other features of my improved device are shown in the accompanying drawing in which the reference characters of the description are applied to like parts in the different views.

In the drawing Figure 1 illustrates in perspective the lower portion of a scenery brace having the device of my invention employed therewith and Fig. 2 is a sectional elevation of my improved hand screw.

In the figures 1 indicates the lower end of the usual stage scenery brace having secured to it the curved foot-iron 2 having a plurality of apertures 3 therein to receive the securing screw, this being of the ordinary type in common use. Fitted to one of the apertures 3 is shown the hand-screw of my invention comprising the lower screw portion 5 having integrally formed therewith a flat collar flange 6 and an upwardly extending squared shank 8. The shank 8, as shown, passes upwardly through an aperture 3 of the foot iron and the screw handle-portion 10 is fitted thereon, so that they

will turn together, by having its central collar portion 11 provided with a squared recess 12 snugly fitting the squared shank 8. In this position, as shown, the foot iron is arranged between the screw flange 6 and a corresponding flange 14 on the central portion 11 of the handle and in this position it is permanently clamped by means of a suitable set screw 15 carried in the portion 11 to be screwed home into small notches 16 formed in the squared screw shank 8. The set screw 15 is desirably countersunk and round-headed so as not to interfere in the manipulation of the handle. In consequence of this arrangement it will be seen that my improved hand screw is permanently clamped on the foot iron 2, of simple construction and as ordinarily used, thus converting it into a complete attaching device in a most economical manner. Furthermore the replacing of the screws 5 and the attachment of the hand-screw as a whole to the foot-iron is accomplished in a single operation or as aforesaid my improved hand-screw may be used in the ordinary manner with the lower clamping flange 6 resting on the foot iron.

I am aware that certain forms of stage-screws permanently secured to the foot-irons have been suggested, but those with which I am acquainted were single-piece screws, so that when worn or broken the whole screw has to be thrown away, and this is one of the disadvantages that I have overcome.

Having described my invention, I claim,—

1. A stage screw comprising a screw element, an upwardly extending squared shank integral with the screw element, a handle element having a recessed collar fitted to the shank to secure them to turn together and a set-screw in the collar to engage the shank for the permanent attachment of the screw and handle elements.

2. A stage screw comprising a screw element, a clamping portion on said screw element, an upwardly extending shank on the screw-element, a handle element, a co-operating clamping portion on the handle element, said handle-element being recessed to receive the screw-shank and means to secure the handle and screw elements in a fixed relation.

3. A stage screw comprising a screw element and a handle element, opposed clamping portions on each of said elements, a

shank on one of the elements, and engaging means on the other element to engage said shank to couple the parts together.

4. A stage screw device for a scenery-brace having a foot-iron attached thereto, comprising a screw-element, a shank on the screw-element to upwardly extend through the foot-iron, a clamping surface on said screw-element to engage the under surface 10 of the foot iron, a handle element to engage with the foot-iron upper surface, said handle element being recessed to receive the screw-shank and means to secure the handle and screw elements in a fixed relation.
- 15 5. A stage screw device for a scenery-brace having a foot iron attached thereto, comprising a screw-element, a squared shank on the screw-element to upwardly extend

through the foot-iron, a clamping collar on the screw-element to engage the under surface of the foot iron, a handle-element, a coöperating clamping collar on the handle-element to engage the foot-iron upper surface, said handle-element having a squared recess fitted to the screw-shank thereby to 25 turn together and a set screw carried by the handle-element to engage the shank and secure the parts.

In testimony whereof I have signed my name to this specification in the presence of 30 two subscribing witnesses.

HARRY FOSTER LEES.
